Andrew K. Foulkes

UNITED STATES PATENT OFFICE

2,144,108

HEATING APPARATUS

Andrew K. Foulds, Grosse Pointe Park, Mich., assignor to Detroit Lubricator Company, Detroit, Mich., a corporation of Michigan

Application April 11, 1936, Serial No. 73,833

6 Claims. (Cl. 122—32)

My invention relates generally to heating systems and more particularly to heating systems for heating water for domestic use.

One of the objects of my invention is to provide a new and improved heating system in which hot water for domestic use is heated by a furnace in winter and by a second heating means in summer, and to provide a system of this character which is economical in operation.

Another object of my invention is to provide a heating system of the above mentioned character in which heating of the furnace boiler water by the second heating means is prevented.

The invention consists in an improved heating system and combination of parts thereof, to be more fully described hereinafter and the novelty of which will be particularly pointed out and distinctly claimed.

In the accompanying drawing, to be taken as a part of this specification, I have fully and clearly illustrated my invention, in which drawing—

The figure is a diagrammatic view of a heating system embodying my invention.

Referring to the drawing by characters of reference, the numeral 1 designates in general a heating apparatus or furnace of the type employed in systems using steam or hot water as the heating medium, the furnace 1 including a boiler 2 in which water is heated and from which the water or steam is conveyed to radiators (not shown) of the system. Associated with the heating apparatus 1 there is a storage tank 3 for hot water for domestic use, the storage tank 3 having a conduit or pipe 4 connected thereto through which cold water is supplied to the tank and having a pipe or conduit 5 through which hot water leaves the tank for domestic use. In the present system the water in the storage tank 3 is heated by the heating apparatus 1 during the heating season, or when the temperature of the water in boiler 2 is at, or above a predetermined temperature, and to heat the water in the storage tank 3 by the heating apparatus 1 an indirect heater or heat exchange unit 7 of any suitable type may be employed.

The indirect heater or heat exchange unit 7 is disposed externally of the boiler 1 and includes a tank or container 8 which is connected to the boiler 2 by upper and lower conduits or pipes 9 and 10 respectively. The upper conduit 9 has one end secured in and to the side wall of the boiler 2, adjacent the upper end thereof, and has its other end secured in and to the top wall of the heater tank 8. The lower conduit 10 has one end secured in and to the side wall of the boiler 2, ad-

jacent the lower end thereof, and has its other end secured in and to the bottom wall of the heater tank 8. The boiler 2, conduits 9, 10 and tank 8 cooperate to provide a circulatory system through which water from the boiler 2 circulates by gravity.

Disposed in the tank 8 of the heater 7 there is a coiled conduit or pipe 11 whose upper and lower ends are connected to conduits 12 and 13 which connect the coiled conduit 11 to the storage tank 3. One end of the conduit 12 may be secured in and to the side wall of the storage tank 3 at a point adjacent the upper end of the tank, and one end of the conduit 13 may be secured in and to the bottom wall of the storage tank. The coiled conduit 11 in heater tank 8, the storage tank 3, and the connecting conduits 12 and 13 cooperate to provide a circulatory system for water in tank 3 to circulate to be heated by the boiler water passing through tank 8.

A second heating means such as a gas burning heater 15 is employed for heating the water in the storage tank 3 when the heating apparatus 1 is not operating, or when it is operating at low fire insufficient to heat the water in tank 3 to the desired temperature. The heater 15 has the usual housing 16 enclosing a main burner (not shown) and enclosing a coiled tube or conduit 17 heated by the burner. The upper end of the coiled conduit 17 is connected to the conduit 12 of the storage tank circulatory system by a conduit or pipe 18, and the other or lower end of the coiled conduit 17 is connected to the lower conduit 13 of the storage tank circulatory system by a conduit or pipe 20. The coiled conduit 17 of the heater 15 is thus in parallel with the storage tank 3 and the heater tank 8. A fuel supply conduit or pipe 21 leads to the burner of the heater 15, and in the fuel supply conduit 21, adjacent the underside of the heater 15, there is preferably provided a manually operable valve 22 for stopping flow of fuel to the burner. The fuel supply conduit 21 extends upwardly adjacent the side wall of the storage tank 3, and connected in the conduit 21 there is a thermostatic valve 23 operable in response to the temperature of the water in storage tank 3 for controlling flow of fuel to the burner of heater 15. The valve 23 comprises in general a casing 24 having a valve port controlled by a valve member 25 which is actuated by a temperature responsive element or bulb 26. The valve casing 24 has an open end disposed toward and secured to the wall of the storage tank 3, the storage tank having an opening in alignment with the open end of the valve casing and

through which the bulb element 26 projects into the storage tank. The bulb element 26 may be charged with a suitable expansible and contractible fluid responsive to changes in temperature.

5 6 Preferably a casing 27 surrounds the bulb element 26 to shield the bulb element from the water in tank 3 and to prevent contamination of the water in tank 3 by the expansible-contractible fluid in the event of a leak developing in the bulb element. Connected to the valve casing 24 on the inlet side thereof is one end of a conduit or tube 30, the other end of the conduit 30 being connected to a constantly burning pilot light (not shown) for lighting the main burner of the heater 15.

10 15 In order to prevent the heating of the water in the boiler 2 by the heater 15 and thereby effect a saving in fuel, I provide a temperature responsive device or valve 31 in the conduit 12 of the storage tank circulatory system intermediate coils 11 and 17 for stopping circulation of the water through coil 11 with resultant stopping of heat transfer from the water in the storage system to the water in the boiler when the temperature of the boiler water decreases to a predetermined temperature. The control device 31 includes a temperature responsive element or bulb 32 projecting into the boiler 2, the bulb being connected to the valve casing by a tube or conduit 33. Preferably the bulb 32 is surrounded and enclosed by a casing 34. The bulb 32 may be charged with any suitable expansible-contractible fluid responsive to changes in temperature for opening and closing the valve.

20 25 30 35 The operation of the above described system is as follows: During the heating season when the temperature of the boiler water is above the temperature for which the thermostatic valve 31 is set to close, hot water from the boiler will circulate by gravity through conduit 16, tank 8 and conduit 9 and back to the boiler. Water from the storage tank 3 circulating through the coiled conduit 11 in heater tank 8 will be heated by the boiler water and thus the water in tank 3 will be heated. When a low fire is desired in the heating apparatus 1, as in the spring or fall of the year, the temperature of the boiler water may not be sufficiently high to heat the water in the storage tank to the temperature desired. When this condition exists the thermostatic valve 23, responsive to the temperature of the water in the storage tank 3, opens to permit flow of gas to the burner of heater 15, the gas being lighted by the constantly burning pilot light. Water in the storage tank 3 then circulates through the coil 17 of the gas heater 15 and is heated. However, when the temperature of the boiler water decreases to a temperature insufficient to heat the water in the storage tank to the desired temperature, the thermostatic valve 31 in conduit 12 40 45 50 55 60 65 70 75 closes and stops flow of storage tank water through coil 11 so that the boiler water is not heated by the gas heater 15. When the water in the boiler 2 is again increased to the required temperature, the thermostatic valve 31 will open permitting circulating of storage tank water through the coil 11 of the heater 7. When the temperature of the water in the storage tank 3 is increased to the desired temperature, the thermostatic valve 23 will act to stop flow of fuel to the main burner of the gas heater 15 to discontinue heating of the storage tank water by the heater 15.

What I claim and desire to secure by Letters Patent of the United States is:

1. In a heating system, a heating apparatus including a boiler for water to be heated, a storage tank for hot water for domestic use, conduit means cooperating with said storage tank to provide a circulatory system for the water in said tank, second conduit means, said second-named conduit means cooperating with the boiler of said heating apparatus to provide a circulatory system for the boiler water, said circulatory systems having portions thereof in heat exchange relation to heat the storage tank water by said heating apparatus, and a temperature responsive device in said first-named conduit means and operable in response to the temperature of the water in the boiler for controlling circulation of water through said first-named conduit. 5 10 15

2. In a heating system, a heating apparatus including a boiler for water to be heated, a storage tank for hot water for domestic use, conduit means cooperating with said storage tank to provide a circulatory system for the storage tank water, second conduit means, said second-named conduit means cooperating with the boiler of said heating apparatus to provide a circulatory system for the boiler water, said conduit means having portions thereof in heat transfer relation to each other to heat the water in the storage tank by the heating apparatus, a second heating apparatus for heating the water in said storage tank, and a temperature responsive device in said first-named conduit means for controlling flow therethrough, said temperature responsive device being operable in response to a predetermined decrease in boiler water temperature for stopping circulation in said first-named conduit means to prevent the heating of the boiler water by said second-named heating apparatus. 20 25 30 35

3. In a heating system, a heating apparatus having a boiler wherein water is heated, a storage tank for hot water for domestic use, conduit means cooperating with said storage tank to provide a circulatory system for the water in said storage tank, conduit means cooperating with the boiler of said heating apparatus to provide a circulatory system for the boiler water, said conduit means having portions thereof in heat transfer relation with each other for heating the water in the storage tank by said heating apparatus, a second heating apparatus for heating the water flowing through said first-named conduit means when the temperature of the boiler water decreases to a predetermined temperature, and a temperature responsive device in said first-named conduit means, said temperature responsive device being operable upon a decrease in the boiler water temperature to said predetermined temperature for stopping flow through said first-named conduit to prevent heating of the boiler water by said second-named heating apparatus. 40 45 50 55 60 65

4. In a heating system, a heating apparatus including a boiler wherein water is heated, a storage tank for hot water for domestic use, conduit means cooperating with said storage tank to provide a circulatory system for the circulation of the storage tank water, said conduit means having a portion thereof in heat transfer relation with the boiler water to heat the water in the storage tank by the heating apparatus, a second heating apparatus, said second-named heating apparatus being connected in said conduit means for heating the water in said storage tank when the temperature of the water in said boiler decreases to a predetermined temperature, temperature responsive means operable in response to 70 75

the temperature of the water in said storage tank for controlling operation of said second-named heating apparatus, and temperature responsive means in said conduit means between 5 said portion and said second-named heating apparatus and responsive to the temperature of the boiler water for controlling flow through said conduit means portion to prevent the heating of the boiler water by said second-named heating apparatus.

10 5. In a water heating system, a water storage tank, a heating apparatus including a chamber for a heated liquid medium, a heat exchange device having a pipe coil positioned in said chamber, conduit members communicatively connecting the ends of said pipe coil and the interior of 15 said storage tank, an auxiliary heating means for heating the storage tank water, a conduit member by-passing said pipe coil and connected to said conduit members and subject to the temperature of said auxiliary means so that the storage tank water may be heated by said auxiliary 20 means and having its ends communicatively connected with the interior of said storage tank at different levels so that the storage tank water may be heated by said auxil-

iary means, a valve for stopping flow through said coil, and means responsive to temperature of said liquid medium to maintain said valve in open position when the temperature of said liquid medium is above a predetermined temperature. 5

6. In a water heating system, a water storage tank, a heating apparatus including a chamber for a heated liquid medium, a heat exchange device having a pipe coil positioned in said chamber, conduit members communicatively connecting the ends of said pipe coil and the interior of 10 said storage tank, an auxiliary heating means for heating the storage tank water, a conduit member by-passing said pipe coil and connected to said conduit members and subject to the temperature of said auxiliary means so that the storage tank water may be heated by said auxiliary 15 means; a valve for stopping flow through said coil, and means responsive to temperature of said liquid medium to maintain said valve in open position when the temperature of said liquid medium is above a predetermined temperature. 20
